United States Patent Office

Des. 185,535
Patented June 23, 1959

185,535

AIRPLANE

Howard Coleman, Albuquerque, N. Mex., assignor of
two one-hundredths to Ernest E. Hatton, Lubbock,
and one one-hundredth to Dudley T. Dougherty, Bee-
ville, Tex.

Application February 2, 1955, Serial No. 34,330

Term of patent 14 years

(Cl. D71—1)

2
FIG

Figure 1 is a front perspective view of an airplane showing my new design; and

Figure 2 is a rear perspective view of the airplane.

The side of the airplane opposite that shown in Figs. 1 and 2 is the same in appearance as the side shown.

I claim:

The ornamental design for an airplane, as shown and described.
